FREDERIC COOKS IMPROVED
METHOD OF VAPOURISING & BURNING HYDROCARBON
FLUIDS AS FUEL

PATENTED

JAN 21 1868

United States Patent Office.

FREDERIC COOK, OF NEW YORK, N. Y.

Letters Patent No. 73,506, dated January 21, 1868.

IMPROVEMENT IN HYDRO-CARBON BURNERS.

The Schedule referred to in these Letters Patent and making part of the same.

TO ALL WHOM IT MAY CONCERN:

Be it known that I, FREDERIC COOK, of the city of New York, county and State of New York, have invented a new and useful "Method of Vaporizing and Burning Hydro-Carbon Fluids as Fuel;" and I hereby declare that the following is a full and exact description thereof, reference being had to the accompanying drawings, and to the letters of reference marked thereon, in which like letters refer to like parts.

The nature of my invention consists of the introduction and distribution of hydrocarbon liquids into furnaces for fuel by means of centrifugal force, either alone, or in combination with water, steam, hot or cold air. In the drawings annexed—

Figure 1 represents an external plan of one manner of injecting the oil and spreading it in the furnace by centrifugal force.

Figure 2 is a horizontal section through line A B.

Figure 3 is an end view.

Figure 4 shows an application of the invention to an ordinary puddling-furnace in longitudinal section.

The hydrocarbon fluid is admitted from a tank into the pipe C, which has stop-valves in it to regulate the supply. The pipe C conveys it to the revolving distributor D, which receives a rotary motion by means of a belt working on the pulley E, or in any other suitable manner. The distributor D, which revolves or vibrates, has a suitable head, F, at the end, which discharges and distributes the fluid into the furnace by centrifugal force, produced by a rotary (or vibrating) motion. G is a bearing, for the pipe D to revolve in, and G, if necessary, may be made hollow, and water allowed to circulate through it to keep it cool. H is a cap, into which the oil-pipe C is fitted, and in which one end of the revolving distributor D works in a V-socket, but a stuffing-box can be used for the same purpose. I is a plug, by removing which a cleaner can be introduced into the distributor D, to cleanse it of sediment or coke. J is a pipe, to admit a jet of water to mingle with the oil, and to be distributed in furnace with it, and thus produce steam inside the furnace. The hydro-carbon fluid should be heated before passing in to the distributor. K are lugs cast on the bearing G, to bolt the cap H to, which is drawn up by the bolts L, and keeps the V-socket-joint tight between it and the revolving distributor D. The revolving distributor D may be driven by connecting it to any description of blower, for creating a forced blast of cold or hot air, or air and steam, into the furnace, or it may be driven by a rotary or other engine directly attached to the distributor, or by intermediate connections, the said engines working by means of steam, compressed air, or water under pressure, or by any other suitable means. M is a tile-plate or fire-brick wall, having perforations for admission of hot or cold air, either by natural or forced draught. N is a pan, to catch any of the fluid hydro-carbon that may drop from the distributor D unconsumed. O is an air-space, and P a draught-door. Q is a hole through brick-work, to admit air to furnace.

When this method is used of burning hydro-carbon fluids as fuel in steam-boiler or other furnaces, the distributor can be attached in any position at any convenient place, such as the furnace-door, ash-pit, or passed through the water-legs of the boiler, or in any other suitable location, or it can be so arranged that the hydro-carbon fluid will drop on to a revolving distributor of suitable form, which will spread it in the furnace.

What I claim as my invention, and desire to secure by Letters Patent, is—

1. The introduction and distribution, by centrifugal force, of liquid hydro-carbons into furnaces as fuel, substantially as shown and described.
2. I claim the introduction and distribution of water, in combination with liquid hydro-carbon, into furnaces by centrifugal force, substantially as shown and described.
3. I also claim the revolving distributor D, with its head F; constructed, arranged, and operating as and for the purpose set forth.

FREDERIC COOK.
